189,221

MOTION PICTURE FILM VIEWER OR SIMILAR ARTICLE

Eugene Martinez, 28 Jaffray Park,
Irvington on Hudson, N.Y.

Filed Nov. 16, 1959, Ser. No. 58,361

Term of patent 14 years

(Cl. D61—1)

FIG. 1

FIG. 2

Fig. 1 is a perspective view of a motion picture film viewer or similar article looking down at the front thereof, showing my design; and

Fig. 2 is a perspective view looking up at the rear thereof.

Portions of the drawings figures are stippled to indicate contrast in appearance.

I claim:

The ornamental design for a motion picture film viewer or similar article, substantially as shown and described.
